[57] CLAIM

The ornamental design for an aerosol inhaler, as shown and described.

DESCRIPTION

FIG. 1 is a perspective view of an aerosol inhaler, showing our new design with the outlet cover installed;

FIG. 2 is a front view of the inhaler of FIG. 1,

FIG. 3 is a rear view of the inhaler of FIG. 2, the opposite side view being identical thereto;

FIG. 4 is a side view of the inhaler of FIG. 2;

FIG. 5 is a top view of the inhaler of FIG. 2;

FIG. 6 is a bottom view of the inhaler of FIG. 1;

FIG. 7 is a perspective view of the inhaler of FIG. 1, showing the outlet cover removed;

FIG. 8 is a front view of the inhaler of FIG. 7; and,

FIG. 9 is a side view of the inhaler of FIG. 8.

The broken line showing of the aerosol canister in the FIGS. 2,3,4,5,8 and 9 is for illustrative purposes only and forms no part of the claimed design.
